CLAIM

The ornamental design for a draw and return tube assembly, as shown and described.

DESCRIPTION

FIG. 1 is a detailed isometric view of the top plate of the draw and return tube assembly;

FIG. 2 is an isometric view of the draw and return tube assembly;

FIG. 3 is a top plan view thereof;

FIG. 4 is a bottom plan view thereof;

FIG. 5 is a right side elevational view thereof;

FIG. 6 is a front elevational view thereof;

FIG. 7 is a left side elevational view thereof;

FIG. 8 is a rear elevational view thereof; and,

FIG. 9 is a detailed left side elevational view of the top plate thereof.

The broken lines in the drawing depict portions of the draw and return tube assembly that form no part of the claimed design.

1 Claim, 8 Drawing Sheets
